US00D515554S

(12) **United States Design Patent** (10) Patent No.: **US D515,554 S**
Kwon et al. (45) Date of Patent: **** Feb. 21, 2006**

(54) **WIRELESS RECEIVER**

(75) Inventors: **Young-Sam Kwon**, Seoul (KR);
Won-Gab Byun, Seoul (KR)

(73) Assignee: **Samsung Electronics Co., Ltd.**,
Kyunggi-do (KR)

(**) Term: **14 Years**

(21) Appl. No.: **29/217,927**

(22) Filed: **Nov. 23, 2004**

(51) LOC (8) Cl. **14-03**

(52) U.S. Cl. **D14/188**

(58) Field of Classification Search **D14/188**,
D14/137, 138, 155, 144, 129, 265, 191-194;

455/347-351; 369/1, 6, 7, 12

See application file for complete search history.
